UNITED STATES PATENT OFFICE.

ELY KASRALOWICZ, OF POUGHKEEPSIE, NEW YORK.

METHOD OF SEWING SLEEVES INTO GARMENTS.

Application filed March 22, 1924. Serial No. 701,083.

To all whom it may concern:

Be it known that ELY KASRALOWICZ, a citizen of the Republic of Russia, residing at 144 Church Street, in the city of Poughkeepsie, in the county of Dutchess and State of New York, U. S. A., has invented certain new and useful Improvements in Methods of Sewing Sleeves Into Garments, of which the following is a specification, 10 reference being had therein to the accompanying drawing.

This invention relates to a method of sewing sleeves into garments, such as coats and dresses.

15 In the manufacture of garments of this class, to produce the fullness required in the sleeve, the upper end of the sleeve is always made much larger than the arm hole in the garment, and the sleeve is gathered 20 to reduce it to the size of the arm hole, and this operation is first done by basting pieces of tape to the sleeve edge to hold the fullness while the sleeve is sewed into the garment, and as the operator sews in the sleeve 25 he is obliged to adjust, reduce or enlarge this fullness as necessary to insure a correct fit, and in so doing the tape becomes broken and much time is consumed in the operation, and skilled labor required.

30 The object of the present invention, is to provide a means whereby the sleeve can be prepared and the fullness gathered in a quick and efficient manner and by unskilled labor, and the time and labor of sewing the 35 same into the garment greatly reduced.

Another object of the invention is that the sleeve may by this method be sewed into the garment from the sleeve side, meaning the inside of the sleeve thus making it much 40 easier for the operator to handle the garment on the machine.

With these and other objects in view, my invention consists in certain combination of parts and materials as will hereinafter be 45 fully described and claimed, and illustrated in the accompanying drawings which form a part thereof and in which like figures of reference refer to corresponding parts in all of the views, but it is understood that 50 while I have described the invention as here shown that slight changes may be made without departing from the spirit of the invention.

In the drawings:—

Figure 1 shows the top part of a sleeve, 55 with the gathering and retaining stitching in place.

Figure 2 shows the arm hole of the garment, which is approximately of the same size as the reduced portion of the sleeve. 60

Figure 3 shows a shuttle and bobbin of the kind used on double thread machines, with a special tension device embodied therein.

Figure 4 is an end view of the bobbin. 65

Referring to the drawings, the invention comprises in combination with a double stitch machine, of a method of employing in place of the lower thread as fed from the bobbin, of a thread composed of rubber 70 or other suitable material, which is fed to the machine under tension, and combined with the upper thread as fed by the needle, will as secured to the cloth, effect a contraction or will gather the same as the tension of the thread is relieved and the rubber thread contracts pulling the cloth with it, and the amount of such gather may be controlled by the amount of tension with which the rubber thread is fed. 75

In Figure 1, the numeral 1 indicates the sleeve, which is gathered as at 2 by the thread 3, to reduce it to the proper size to conform to and fit the arm hole 4 of the garment. 85

In Figure 3, the usual shuttle 5 is shown, which is attached to the stud 6 secured to the machine 7, by the latch 8 which is hinged to the shuttle and is shown as in the open position. 90

The bobbin 9 which is wound with the rubber thread under tension, that is the rubber thread is stretched in some suitable manner before being wound on the bobbin, and the feeding tension of the same is maintained by any suitable means such as a spring 10 placed between the bobbin 9 and the machine 7, or any suitable mechanism may be employed for feeding the rubber thread to the cloth under tension, and means 100 employed for changing said tension as desired.

The sleeve having been gathered in this manner by the rubber thread retained in place by the usual thread combined or interlaced therewith through the cloth; the 105

rubber thread 12 being on one side of the cloth, as it is not possible to use the same with the needle, as the eye of the needle would cut or break the rubber and also the 5 rubber could not be pulled through the cloth, so for this reason a double thread machine must be employed.

The sleeve is now sewed into the garment by the operator who can lessen or increase 10 the tension or amount of gather at will on account of the rubber thread.

As shown in Figure 3, there is further provided a spring 11, secured to the latch 8, which when the shuttle 5 is in place and the 15 bobbin 9 inserted, will press against the end of the bobbin 9 producing tension.

The shuttle 5 is provided with the usual hole 12 through which the thread is fed.

While it is not here shown, there may be 20 employed in place of the rubber thread, a rubber tape, which can be sewed to the goods in the usual way, but the thread has been found to produce the best results.

It should also be noted that to allow of 25 the further stretch or elongation of the rubber thread, the needle thread should be operated with very little tension when sewing.

Having thus described my invention, what I claim as new and desire to secure by Letters Patent, is:

1. A method of sewing sleeves into garments, comprising, first gathering the fullness of the sleeve with a rubber thread, and then sewing said sleeve into the garment.

2. A method of sewing sleeves into garments, comprising, first gathering the fullness of the sleeve with a rubber thread under tension, and then sewing the sleeve into the garment in the usual manner.

3. A method of attaching sleeves to garments, comprising in connection with a double thread machine, employing the usual needle thread, of a rubber bobbin thread and means for feeding the same to the cloth under tension.

4. In a method of sewing sleeves into garments, in combination with the usual needle thread, of a rubber thread fed under tension and combined with the other thread to produce fullness or gathers in said sleeve to reduce the size of the same at the arm hole.

In testimony whereof I hereunto affix my signature.

ELY KASRALOWICZ.
